TOE SHIELD

Application filed August 5, 1930. Serial No. 473,192.

This invention relates to a toe shield or cushion, and more particularly to such a device to be used by toe dancers.

In toe dancing or ballet dancing considerable strain is placed on the toe portion of the foot of the dancer, and this is true regardless of whether ballet slippers or toe slippers are used. In an attempt to relieve the dancer from this strain and the attendant pain, it has been the practice to employ slippers considerably larger than the foot and to insert a filling of lamb's wool in the toe of the slipper. This filling, however, is soft only at first, and soon packs down and hardens. It also tends to move around in the slipper and consequently is often made ineffective. The lamb's wool ordinarily must be replaced with a fresh supply each time the slippers are worn.

As a result of the inconvenience and unsatisfactoriness of lamb's wool, numerous attempts have been made to devise a toe cushion or pad or buffer made of rubber or like resilient material, which may be used more or less indefinitely without packing and losing its softness and yieldability. However, such devices have not met with appreciable success because of a number of difficulties and disadvantages, which it is the primary object of my invention to obviate and overcome.

When the forward end or tip of a toe shield is made of solid rubber, it is difficult to obtain a maximum degree of resilience or yieldability so as to cushion the foot of the dancer with the desired effectiveness. Accordingly, one object of the present invention is to improve the cushioning effect of a rubber toe shield, and this I have found may be accomplished by hollowing the outer surface of the forward end of the cushion so as to form a recess or concavity or air pocket. With such a construction I find that the natural resiliency of the rubber material may be fully utilized, and that the cushioning effect obtained is superior to that obtained with newly inserted lamb's wool, and is far superior to that obtainable with a solid body of rubber.

The toe shield ordinarily comprises a cup-shaped device adapted to receive the toe por-

tion of the foot of the dancer. As heretofore constructed, such a device would encompass and rather closely fit the toe portion of the foot. When the weight of the dancer is placed on the toe of the foot, the toe portion of the foot spreads laterally and is consequently bound by the toe shield. This is directly injurious to the foot, and after a few minutes of use becomes indirectly injurious to the foot because of the resulting perspiration and total absence of ventilation. Incidentally, such a construction is inconvenient because numerous sizes of toe shield must be provided corresponding to the various sizes of foot and slipper.

Further objects of my invention are to overcome all of the foregoing difficulties and to provide a toe shield which will not hug and bind the toe portion of the foot; which will sustain and protect the toe portion of the foot when on the toe, but which is released from close contact with the foot when on the sole; which will permit air to circulate around the foot; and which will be of such a nature that a single size of shield may be used for the entire range of sizes of foot and slipper. With these objects in view, a portion of the cup-shaped shield, preferably the bottom or sole portion, and, if desired, the top portion also, is cut away in order to permit the sides of the shield to readily move laterally without binding the foot of the dancer. The shield is free on the foot of the dancer and also is free within the slipper. When the weight of the dancer is placed on the toe, the spread of the foot causes it to bear against the sides of the cushion, which in turn bear against the sides of the slipper, thereby protectively housing the toe portion of the foot. When, however, the dancer rests on the sole of the foot, the side pressure is immediately relieved, and the fit between the foot, the sides of the shield, and the sides of the slipper is sufficiently free to facilitate ventilation of the foot.

Because of the downward movement of the foot when on the toe, together with the expansion thereof laterally, there is a tendency for the top of the shield to turn inwardly and to cut into and bind the foot.

This is particularly true at the upper portion of the shield. Another object of the present invention is to overcome this fault, and for this purpose the edge portion of the shield is turned outwardly, or, more specifically, 5 the edge of the upper portion of the shield is turned upwardly. In actual use the pressure of the foot may cause the outwardly turned edge to be flattened against the inner 10 surface of the slipper, but the edge can never turn inwardly and cut into the foot.

It has previously been pointed out that one of the important faults of rubber shields resides in their tendency to cause excessive 15 perspiration of the foot, and the absence of ventilation to counteract this tendency. In accordance with a further feature and object of the present invention, vents or perforations are provided in the shield at points so 20 selected that there is a tendency not only to permit air circulation, but actually to pump air around the toe portion of the foot. For example, an air vent is provided in the concavity at the forward end of the shield, 25 and when the shield is compressed or released, as when the foot changes from sole to toe or from toe to sole, air is forced through the shield and around the toe portion of the foot, thereby effectively ventilating the same. Additional 30 perforations are placed in the sides of the shield, and the spreading or lateral movement of the same when the foot changes from sole to toe or vice versa also tends to cause free ventilation of the foot.

To the accomplishment of the foregoing and such other objects as will hereinafter appear, my invention consists in the toe shield or cushion elements and their relation one to the other as hereinafter are more particularly described in the specification and 40 sought to be defined in the claims. The specification is accompanied by drawings in which:

Fig. 1 is a partially sectioned plan view 45 of a shield embodying my invention;

Fig. 2 is a side elevation of the same;

Fig. 3 is a vertical section taken in the plane of the line 3—3 in Fig. 1;

Fig. 4 is a plan view of a toe slipper in 50 which my shield has been placed; and

Fig. 5 is a partially sectioned elevation of the same when on the toe.

Referring to the drawings, my toe shield or cushion comprises a cup-shaped device 12 55 which is preferably made of a light, soft, sponge-like, medicated rubber, or any other suitable resilient material. The periphery of the forward end of the shield is preferably made of a thick body of rubber, as is indicated at 14. The entire forward end, however, is not made of this thickness, but instead is hollowed out or cut away to form the air pocket or recess or concavity 16. The construction is such that the peripheral edge 14 60 rests against the inside surface of the toe of

the dancing slipper. When the weight of the dancer is placed on the toe, the concavity 16 permits the resilient material of the shield to yield freely, and, if desired, this cushioning effect may be enhanced by reason of the air cushion obtained as a result of air being trapped in the concavity 16. In the present form of the invention this air cushioning effect is intentionally neglected in order to obtain forced air circulation and ventilation in a manner subsequently explained.

From the forward edge 14 of the shield, the material is gradually and smoothly tapered down to an exceedingly thin or feather edge 18 at the rear of the shield. A portion of the cup-shaped shield is cut away to permit the sides to readily move laterally without binding the foot of the dancer. For this purpose it is preferable to cut away the bottom or sole portion of the shield, as is indicated at 20. Here, also, the rubber material is tapered off into a fine edge so that the foot of the dancer is not subjected to any noticeable ridge.

The sides 22 of the shield extend back from the tip of the shield further than the box of a conventional box toe dancing slipper, so that if the slipper has been poorly made and has a noticeable stiff edge at the termination of the box, the sides of the shield will protect and cushion the foot against such an edge when the foot is on the toe.

The upper portion of the shield is also preferably cut away, as is indicated at 24, for several reasons. In the first place, this facilitates the desired lateral movement or expansion of the sides of the shield. In the second place, it reduces the area of the toe portion of the foot surrounded by rubber and therefore reduces perspiration, and increases ventilation. In the third place, it insures that the shield will not project beyond the edge of the ballet slipper thereby exposing it to view. In the fourth place, by cutting away the upper portion of the shield to a considerable extent, it is possible to so proportion a single size of shield that it may be used with any size of slipper. This accommodation of a wide range of size is made possible because the shield rests against the inner face of the toe of the slipper on the peripheral edge 14 and need not contact with the slipper at any other point. The sides of the shield readily expand to accommodate different sizes of foot, and if the upper portion is cut away in the manner just described so as not to be visible when placed in a small size slipper, a single size of shield suffices for all sizes of slipper. A smaller size shield may, if desired, be provided for small children.

To prevent the upper edge of the shield from cutting into the foot, which would ordinarily take place because of the movement of the foot toward the tip of the shield when

on the toe, accompanied by the simultaneous expansion of the foot, the edge is initially turned outward or upward, as is indicated at 26. This upturning of the edge is carried 5 backward entirely along the sides of the cut away portion 24. The resulting edge is flattened against the inner surface of the slipper when the weight of the dancer is on the toe, as is best shown in Fig. 5, but this edge can 10 never turn in so far as to cut into the foot. A similar precaution may be taken at the bottom of the shield, but this I have found is unnecessary, for the weight of the dancer rests constantly against the lower surface of 15 the shield, and even when the foot is on the toe there is no tendency for the bottom edges to cut into the foot, for the expansion and curvature of the foot is toward the upper portion of the foot, rather than the lower. 20 The usual difficulty experienced with a rubber shield or cushion in the way of excessive perspiration and total lack of ventilation is very largely obviated in the present shield, by reason of the fact that the upper 25 and lower surfaces are for the most part cut away, as at 20 and 24. In addition, I provide the shield with a plurality of vents or perforations 30 distributed along the sides of the shield. These vents function not only 30 to permit air circulation, but because of the nature of the present shield and its action during the dance, there is a positive tendency to circulate air through the vents. To explain this further, attention is directed to 35 Fig. 4 in which it will be observed that the outer surface of the sides 22 of the shield are spaced from the inner walls 34 of the toe slipper in which the shield is placed. In fact the shield bears against the slipper only at 40 the forward periphery 14 which rests on the inner wall 36 at the toe of the slipper. When the dancer is resting on the sole of the foot, the foot is relatively free in the shield, inasmuch as the sides of the shield may readily 45 spread apart, and the sides of the shield are themselves relatively free in the slipper. When the weight of the dancer is placed on the toe of the foot, the foot spreads into contact with the sides 22 of the shield, and they 50 in turn spread into contact with the side walls 34 of the slipper. During the changes from sole to toe and vice versa in the dance, the resulting lateral movement of the sides of the shield tends to circulate air through 55 the vents 30 and around the toe portion of the foot. 60 It has previously been explained that the concavity 16 at the tip of the shield increases the resiliency and yieldability of the forward end thereof. It has also been mentioned that the air trapped in the concavity 16 may, if desired, be used for its additional cushioning effect. In the present case an additional 65 perforation or vent 38 is provided in the forward surface of the shield through which air is circulated to further ventilate the foot of the dancer. It will be evident from the foregoing description, or from a comparison of Figs. 3 or 4 of the drawings with Fig. 5, that the volume of the recess or concavity 16 is considerably diminished when the weight of the dancer is placed on the toe, and is again restored when the weight of the dancer is placed on the sole of the foot. This change in volume effectively pumps air through the 70 vent 38 and around the toe portion of the foot of the dancer. 75 The manner in which the toe shield or cushion of my invention may be constructed and used, and the many advantages thereof, will, it is thought, be apparent from the foregoing detailed description thereof. The toe cushion is far superior to lamb's wool because it does not harden and cannot move around within the slipper. It may be used over and over again and may be moved from slipper to slipper, and in fact may be used in different sizes of slipper. A smaller size of slipper may be used than when cushioning with lamb's wool, for only a half size need be allowed for the shield, whereas it is customary to allow two half sizes or a full size for the body of lamb's wool. The cushioning effect obtained is remarkably good, due to the provision of the air pocket or concavity at the forward end of the shield, which permits the resilient material of the shield to yield freely. The sides of the shield are carried back sufficiently far to protect the foot against poorly made toe slippers and to distribute the weight 90 of the dancer over a large area when on the toe, and yet hugging and binding of the foot are prevented because the upper and lower portions of the shield are very largely cut away. This construction aids ventilation of 95 the foot, and additional air circulation is provided in a positive manner by the provision of vents properly located to take advantage of the movement of the shield caused by shifting of the weight of the dancer from the sole 100 to the toe or vice versa. The edges of the shield are tapered and reduced in thickness so as not to form a noticeable ridge, and the upper edge is turned upwardly to prevent it from cutting into the foot. 105 110 It will be apparent that while I have shown and described my invention in the preferred form, many changes and modifications may be made in the structure disclosed without departing from the spirit of the invention, 115 defined in the following claims. 120

I claim:

1. A shield or cushion for toe dancers, the outer surface of the forward end of which is hollowed out to form a concave surface 125 so as to increase the yielding effect of said cushion.
2. A shield or cushion for toe dancers comprising a cup-shaped device made of a resilient material for receiving the toe portion of 130

- the foot of a dancer, the outer surface of the forward end of said device being hollowed out to form a concave surface so as to increase the yielding effect of said cushion.

5. 3. A shield or cushion for toe dancers comprising a cup-shaped device made of a resilient material, the outer surface of the forward end of said device being hollowed out to form a concave, readily yieldable supporting surface, the resulting concavity being provided with a perforation through which air is circulated when the cushion is compressed or released.

10. 4. A shield or cushion for toe dancers designed for insertion into the toe portion of the ballet slipper or toe shoe used by the dancer, said cushion comprising a cup-shaped device made of a soft resilient material the bottom or sole portion of which is cut away in order to permit the sides of the device to readily move laterally, without binding the foot of the dancer, and the edge of the upper portion of which is feathered and turned upwardly to prevent the same from binding the

20. 25. foot of the dancer.

5. 5. A shield or cushion for toe dancers designed for insertion into the toe portion of the ballet slipper or toe shoe used by the dancer, said cushion comprising a cup-shaped device made of a soft resilient material the top and bottom surfaces of which are cut away for a substantial distance in order to permit the sides of the device to readily move laterally, without binding the foot of the dancer, and the rear edges of which are feathered down to a thin edge.

30. 35. 6. A shield or cushion for toe dancers designed for insertion into the toe portion of the ballet slipper or toe shoe used by the dancer, said cushion comprising a cup-shaped device made of a soft resilient material the top and bottom surfaces of which are cut away in order to permit the sides of the device to readily move laterally, and the edge of the upper portion of which is feathered and turned upwardly to prevent the same from binding the foot of the dancer.

40. 45. 7. A shield or cushion for toe dancers designed for insertion into the toe portion of the ballet slipper or toe shoe used by the dancer, said cushion comprising a cup-shaped device made of a soft resilient material the top and bottom surfaces of which are cut away in order to permit the sides of the device to readily move laterally, the said sides extending back from the toe substantially further than the box or reinforced toe portion of a conventional box toe dancing slipper.

50. 55. 60. 65. 8. A shield or cushion for toe dancers designed for insertion into the toe portion of the ballet slipper or toe shoe used by the dancer, said cushion comprising a cup-shaped device made of a soft resilient material the top and bottom surfaces of which

are cut away in order to permit the sides of the device to readily move laterally, the edge of the upper portion being turned upwardly to prevent the same from binding the foot of the dancer, and the resulting sides extending back from the toe substantially further than the box or reinforced toe portion of a conventional box toe dancing slipper.

70. 75. 80. 85. 90. 95. 100. 105. 110. 115. 120. 125. 130.

9. A shield or cushion for toe dancers comprising a cup-shaped device made of a resilient material, the outer surface of the forward end of said device being hollowed out to form a concave surface so as to increase the yielding effect of said cushion, and the top and bottom surfaces of said device being cut away in order to permit the sides of the device to readily move laterally.

10. A shield or cushion for toe dancers comprising a cup-shaped device made of a resilient material, the outer surface of the forward end of said device being hollowed out to form a concave surface so as to increase the yielding effect of said cushion, the top and bottom surfaces of said device being cut away in order to permit the sides of the device to readily move laterally, and the edge of the upper cut away portion being turned upwardly to prevent the same from binding the foot of the dancer.

11. A shield or cushion for toe dancers designed for insertion into the toe portion of the ballet slipper or toe shoe used by the dancer, said cushion comprising a cup-shaped device made of a soft resilient material, the top and bottom surfaces of said device being cut away in order to permit the sides of the device to readily move laterally, the sides extending back substantially further than the box or reinforced toe portion of a conventional box toe dancing slipper, and said device being provided with a plurality of ventilating holes through which air may circulate when the weight of the dancer is shifted from the sole to the toe and vice versa.

12. A shield or cushion for toe dancers comprising a cup-shaped device made of a resilient material, the outer surface of the forward end of said device being hollowed out to form a concave surface so as to increase the yielding effect of said cushion, and the top and bottom surfaces of said device being cut away in order to permit the sides of the device to readily move laterally, said device being provided with a plurality of ventilating holes through which air may circulate when the weight of the dancer is shifted from the sole to the toe and vice versa.

13. A shield or cushion for toe dancers comprising a cup-shaped device made of a resilient material, the outer surface of the forward end of said device being hollowed out to form a concave surface so as to increase the yielding effect of said cushion, the top and bottom surfaces of said device being cut away in order to permit the sides of the

device to readily move laterally, the edge of the upper portion being turned upwardly to prevent the same from binding the foot of the dancer, and the resulting sides extending back from the toe further than the box of a conventional box toe dancing slipper, said device being provided with a plurality of ventilating holes through which air may circulate when the weight of the dancer is shifted from the sole to the toe and vice versa.

Signed at New York in the county of New York and State of New York this 4th day of August A. D. 1930.
